PUMP

Ellsworth W. Austin, Cedar Rapids, Iowa, assignor to La Plant-Choate Manufacturing Company, Incorporated, Cedar Rapids, Iowa, a corporation of Delaware

Application December 31, 1934, Serial No. 759,944

4 Claims. (Cl. 180—53)

This invention relates in general to pumps and has particular relation to the mounting and arrangement of the parts of such pumps in relation to the parts of a tractor or like prime mover.

While hydraulic pumps are commonly used with tractors and like prime movers, it is the usual practice to mount these pumps at the rear of the tractor and to drive them by extensions of the shafting of the tractor. This rear-end mounting of the pump has several disadvantages. The pumps are in the way in mounting other equipment on the tractor and necessitate the use of various relatively expensive coupling members for driving them and for conveying liquid to and from the pump.

A much more advantageous location of the pump would be at the front of the tractor, where the pump may be driven directly from the tractor motor, without interruption of clutch engagement as is the case with the conventional rear mounting.

There are also several disadvantages present in the pumps known to the art. The pump frequently cannot be made leak-proof, and frequently end-thrust is encountered in the drive shaft by reason of the hydraulic pressure of the fluid being pumped and no means is provided for taking up this thrust or allowing for end-wise movement of the drive shaft.

It is, therefore, a general object of my invention to overcome the difficulties above enumerated and to provide a pump which may be mounted at the front of the tractor.

A more specific object of my invention is to provide means for mounting a pump on the radiator of a tractor.

Another object of my invention is to provide means whereby a crank may be employed for cranking the motor without the necessity of disconnecting or otherwise disturbing the pump.

Another object of my invention is to provide in a pump crank case means for inclosing the pump and pump drive.

Another object of my invention is to provide a seal means for a pump which will permit a controlled seepage from the pump housing into the gear case housing in order that the drive gears may be lubricated.

Another object of my invention is to provide means whereby end-thrust on the drive shaft of the pump will not injure the pump.

Another object of my invention is to provide a metallic seal for pumps that does not require manual adjustment to meet varying conditions of fluid pressure.

Another object of my invention is to provide means for offsetting the pump whereby end-thrust on the pump shaft does not injure the pump parts.

Other and further features and objects of my invention will be more apparent to those skilled in the art upon a consideration of the accompanying drawing and following specification, wherein is disclosed an exemplary embodiment of the invention, with the understanding, however, that such changes may be made therein as fall within the scope of the appended claims without departing from the spirit of the invention.

In said drawing:

Figure 1 is a view in section, taken along the line 1—1 of Figure 2, of a pump and pump mounting constructed according to one embodiment of my invention.

Figure 2 is a view, partly in front elevation and partly in section, of the pump and pump mounting shown in Figure 1; and

Figure 3 is a partial view of the seal means used for sealing the pump shaft with the pump housing.

Referring now to the drawing, there is shown at 10 in outline the radiator of a tractor. An opening 11 is provided through the radiator in which an extension 12 of the crank shaft of the engine or other prime mover of the tractor may extend. A roughly cup-shaped gear housing or case 13 is secured to a suitable flange 14 of the radiator 10 in any conventional manner as by means of bolts or the like. A gear case cover 16 is bolted to the open face of the gear case 13, as

by means of bolts 17, and a cylindrical, forwardly-extending flange 18 of the gear case 16 affords one bearing in which the stationary race 19 of a ball bearing may be located. A circular flange 21 on the rear face of the gear housing 13 affords a mounting means for the stationary race 22 of another ball bearing. A sleeve-like member 23 is threaded into the open end of the cylindrical portion 18 of the gear case cover 16 and this sleeve 23 retains the ball bearing 42 and

serves also as a guide for the crank (not shown) used in cranking the motor. The sleeve 23 is held in place by means of a collar 24. The open end of the sleeve 23 may be covered by a cap 26 which is pivotally movable and pivotally engaged by means of a pin 27 and spring 28. The gear case 13 has an upwardly-extending portion indicated at 13a and the gear case cover 16 likewise has an upwardly-extending portion 16a to

serve as a housing for the pump drive gearing hereinafter more particularly described.

The upper portion 16a of the gear case cover 16 is open at the front thereof and a pump housing 31 is secured to the gear case cover over the open portion as by means of bolts 32. A pump housing cover 33 is secured to the front face of the housing 31 as by means of bolts 34.

In order to facilitate manufacture and assembly of the housing 31 it is preferably made of three parts comprising the plates 31a and 31b and a gear receiving member 31c. Fluid is supplied to the pump through the inlet port 37 and forced outwardly under pressure through the exhaust port 38. Of course the direction of movement of the fluid through the pump depends upon the direction of rotation of the shaft 12, the pump operating in the usual manner of such gear pumps.

20 A short gear drive shaft 41 is mounted for rotation within the gear housing 13 and gear case cover 16 by means of bearings such as the ball bearings 42 and 43 which rotate on races 19 and 22 respectively. Seals 44 are provided 25 on each of the bearings 19 and 22 in accordance with the usual practice. The shaft 41 is splined at the ends thereof, as indicated at 46 and 47, and the shaft is driven by means of a sleeve 48 which engages on spline 46 on shaft 41, and on splines 30 49 of shaft 12. A collar 51 is threaded on the opposite end of the shaft from the sleeve 48, and this collar is provided with a pair of conventional lugs 52 adapted to receive the end of a starting crank (not shown). The collar 51 is 35 locked in place by means of a bolt 53 which is threaded into the end of the shaft 41.

40 A clutch collar 56 is slidingly engaged upon the splined portion 54a of intermediate spacer 54 which in turn is locked in place on splines 47 of the shaft 41 by means of collar 51. The clutch collar 56 is provided with a peripheral groove 56a adapted to receive a yoke 57 for a purpose hereinafter more particularly described. The clutch collar 56 is also provided with lugs 58 which are adapted to engage corresponding lugs 59 on a 45 large gear 61 which is rotatably mounted on shaft 41. The collar 56 is thus adapted to be engaged and disengaged with the gear 61 by moving the clutch collar 56 along the splines 54a of spacer 54.

50 Movement of the clutch collar 56 into and out of engagement with the gear 61 is accomplished by means of the yoke 57 and a crank 62 which is mounted on a shaft 63 extending through the side wall of the housing 13. The yoke 57 is pivotally engaged to the crank 62 by means of a pin 64 which constitutes a part of the yoke and which extends into the crank. The shaft 63 is rotated by means of a lever 66 which is attached on the outer or projecting end of the shaft and extends upwardly therefrom alongside the pump. A plunger 67 is provided in the housing 13 above the crank 62 and a spring 68 biases the plunger downward against the upper face of the crank 62. The upper face of the crank is rounded in such a manner that the yoke is held in one or the other of its extreme positions so that the clutch is either in complete engagement with the gear 61 or is entirely out of engagement.

70 A pump drive shaft 71 is rotatably mounted in the lower portion of the pump housing by means of roller thrust bearings 72 which are mounted within the plates 31a and 31b. The shaft 71 is splined, as indicated at 73, and the pump drive gear 74 may move along the shaft to an extent

which is limited by the plates 31a and 31b. As may readily be understood considerable hydraulic pressure is developed inside the housing 31 and in the chamber 76, and this pressure acts upon the end of the shaft 71 to tend to force it out of the pump housing. I have therefore made the gear 74 slidable on the shaft to prevent undue wear between the side of the pump gear and the plate 31a.

5 The pump drive shaft 71 is driven by means of 10 a pump drive gear 78 which is located on the projecting end of the shaft 71 and which is in mesh with the large gear 61. Endwise movement of the pump drive shaft 71 is limited by the thrust roller bearings 72. A shoulder 89 is 15 provided on the shaft 71 and a collar 91 has the smallest end thereof bearing against the shoulder 89. The pump drive gear 78 in turn bears against this collar and is held in this position by means of the nut 92 which is threaded 20 on the end of the shaft 71.

A relatively heavy pin or shaft 93 is mounted 25 within suitable openings in the plates 31a and 31b and this shaft serves as a journal upon which an idler gear 94 is rotatably mounted as by means of 30 the roller bearings 96. The idler gear 94 is, of course, in mesh with the gear 74 and the two gears are utilized in accordance with the usual principles of operation of gear pumps to pump fluid 35 under pressure.

The fluid usually used with pumps of this type is lubricating oil and this lubricating oil, of course, lubricates the rotating parts of the pump proper. This lubricating oil is quite suitable for lubricating the rotating parts of the drive gear, but it is 40 apparent that if any direct connection were made between the pump housing and the drive gear housing oil under considerable pressure would flow into the drive gear housing and would leak from the housing at both ends of the drive shaft 45 and that an excessive quantity of foreign matter would be carried into the drive gearing. I have accordingly devised seal means for sealing the pump housing 31 where the shaft 71 passes therethrough, which sealing means will permit a 45 limited or controlled flow or seepage of oil from the pump housing into the gear case housing.

In constructing my preferred seal means a cuffed recess 97 is provided in the outer wall of the pump plate 16a. A gasket 98 is placed in this 50 recess and a flexible cuffed diaphragm 99 is placed on this sealing gasket.

A disc-like retaining plate 101 is placed on the diaphragm 99 and the diaphragm seal with its component parts is locked in place in the recess by means of a plurality of bolts 102. The diaphragm 99 is provided with a circular opening at the central portion thereof to receive the shaft 71 and collar 91. A stationary ring 103 is secured to the inner edge of the diaphragm and bears against the rotating collar 91 to form a lap seal with it. The shoulder 100 of the ring, which is preferably of hardened steel or like material, is swaged solidly to the inner edge of the diaphragm, as indicated at 104. The diaphragm 99, before it is 60 assembled on the shaft 71 and the collar 91, has the central portion thereof flexed to the right, as indicated by the dotted lines of Figure 3, but when in position on the pump it is so disposed as to have its convex face bent inwardly towards the direction from which oil escaping from the pump will flow. This engaged position is indicated by the full lines of Figure 3. The oil that flows from the pump housing tends to fill the cavity 106 and the oil pressure within the pump builds up pres- 75

sure against the diaphragm 99. The greater the oil flow from the pump, the greater the pressure within the cavity 106 and therefore the greater the pressure against the diaphragm 99. As the pressure against the diaphragm 99 is increased and by reason of its flexed arrangement it is caused to press against the ring 103 in direct ratio to the pressure within the cavity 106. Furthermore the endwise shifting of the shaft 71 by reason of the changes in oil pressure within the pump also causes variations in pressure of ring 103 against collar 91. It is apparent therefore that the greater the pressure within the pump and within the cavity 106 the greater the pressure of the diaphragm and ring 103 against the collar 91, and consequently the greater the sealing effect. While the sealing effect becomes greater at high speeds, nevertheless the pressure of the fluid is higher and some slight leakage occurs to always provide sufficient oil to lubricate the gears. At slow speeds the biasing action of the diaphragm is sufficient to seal the shaft but will permit some leakage. It is apparent, therefore, that in this manner a controlled flow of oil from the pump housing into the gear case housing results at all speeds.

Although I have described a preferred embodiment of my invention it is apparent that modifications may be made by those skilled in the art. Such modifications may be made without departing from the spirit and scope of my invention as set forth in the appended claims.

I claim as my invention:

1. In combination with a tractor including a radiator and a motor for driving the tractor, a gear housing mounted on the front of the radiator, a drive shaft mounted for rotation within the gear housing, coupling means for connecting the drive shaft with the drive shaft of the motor,

coupling means on the outer end of the drive shaft to permit attachment of a cranking handle, a gear rotatably mounted on the drive shaft, a clutch on the drive shaft for engaging the gear, a pump housing mounted on the gear housing, a 5 pump drive shaft, and a gear on the pump drive shaft adapted to mesh with the gear on the drive shaft.

2. In combination with a tractor, a pump and a gear housing mounted at the front of the tractor, 10 with the gear housing attached to the radiator of the tractor, and clutch means arranged within the gear housing to provide selectively manually engaging and disengaging power means or crank- 15 ing means or both for operating the pump.

3. In combination with a tractor including a radiator and a motor for driving the tractor, a gear housing mounted on the front of the radiator, a drive shaft mounted for rotation within the gear housing, coupling means for connecting 20 the drive shaft with the drive shaft of the motor, coupling means on the outer end of the drive shaft to permit attachment of a cranking handle, a gear rotatably mounted on the drive shaft, a 25 clutch on the drive shaft for engaging the gear, a yoke and crank means for operating the clutch, and a biasing means for keeping the clutch in the engaged or disengaged position.

4. In combination with a tractor including 30 power means, a pump and a gear housing mounted at the front of the tractor, with the gear housing attached to the radiator of the tractor, a pump means, a cranking means for cranking the power means, and clutch means arranged within the 35 gear housing to provide means for manually engaging or disengaging the power means with the cranking means and pump means.

ELLSWORTH W. AUSTIN.
